DESIGN FOR A FOLDED FABRIC FOR LINING CASKETS, OR SIMILAR ARTICLE

Edgar D. Bloxsom, Houston, Tex.

Application August 7, 1933, Serial No. 48,943

Term of patent 14 years

To all whom it may concern:

Be it known that I, EDGAR D. BLOXSOM, a citizen of the United States, and residing at Houston, in the county of Harris and State of Texas, have invented a new, original, and ornamental Design for Folded Fabric for Lining Caskets, or Similar Article, of which the following is a specification, reference being had to the accompanying drawing forming a part thereof.

In the accompanying drawing, the figure is a perspective view of a section of cloth or fabric shown as folded in the particular manner designed by applicant.

I claim:

The ornamental design for a folded fabric for lining caskets, or similar article, substantially as shown and described.

EDGAR D. BLOXSOM.
